INSTALLATION FOR RECOOLING THE COOLING AIR IN CIRCULATING AIR COOLING INSTALLATIONS

Hermann Ortmeyer, Berlin, Germany

Application October 14, 1930, Serial No. 488,564,
and in Germany October 22, 1929

3 Claims. (Cl. 171—252)

My invention relates to installations for re-cooling the air in circulating air cooling installations for electrical machinery, for example, a turbo-generator, although the application of my invention will be understood as not limited to this particular use.

The hitherto known installations of this kind involve a number of considerable disadvantages both of a constructive kind as also in reference to technical operation. Although mostly provided with a sufficiently large cooling surface, they are designed with a too small diameter of the air inlet and with a too great depth, while the cooling ribs are spaced too far from each other. The space required by them is in consequence considerably larger than it would be if they were correctly dimensioned. In the hitherto known cooling installations the water chambers, throttle valves, cooling water collecting pipes, drain cocks, air release cocks and the like are not always separated from the circulating cooling air current, so that leak-water may enter the cooling air current. A great drawback inherent in many cooling installations consists in the fact that the enclosed quantities of air take up too much room, particularly so if the air space is formed between the foundation pillars as a large cooling air chamber, whereby not only the access to important parts of the coolers and condensers is obstructed, but also the natural quenching of a fire breaking out in the windings of the electric machine is unduly delayed.

In accordance with my invention I arrange the cooler elements horizontally, one above the other in front of at least one of the vertical openings of the foundation of the machine. The advantage offered by this arrangement is that the cooler, with a relatively very large inlet diameter for the cooling air only takes up a minimum of ground area. However as in the pillar foundations, which are mostly used to-day for turbo-generators, much space is available, it is possible in an installation according to my invention to provide a cooler of high efficiency even with a very small ground area. The further opportunity, afforded by the small depth of the cooler, of diminishing the distance between the cooling ribs without undue increase of the air resistance, affords an additional possibility of considerably reducing the absolute space required for the cooler in particular and the whole cooling installation in general.

Another object of my invention is to arrange the cooler elements, one above the other, in front of the outer side of the opening in the foun-

dation. This arrangement permits an especially simple arrangement of the condenser in the foundation of the machine, which is particularly suitable for the necessary attendance whenever the cooling installation is used for turbo-generators. Furthermore, it renders it particularly easy to expose the individual elements of the cooler for the purpose of cleaning, even when the cooling plant is in operation.

A further object of my invention is to directly connect the cold air channel extending from the cooler across the foundation with the space between two foundation pillars. This arrangement enables a particularly simple construction of the cold air channel and at the same time creates further space, which can be utilized for the arrangement of the condenser.

In a preferred embodiment of my invention I arrange the cooler elements at right angles to the circulating currents of cooling air, at the same time providing for free movement of the elements in longitudinal direction. Means may be provided, whereby parts of the active cooler surface can be temporarily shielded against the opening in the foundation, so that an exchange of cooler elements is possible even during operation, the arrangement described affording the possibility of removing and re-inserting or replacing the individual cooler elements at any time.

The drawer-like movement of the cooler elements is moreover very simple, occurring directly along a pillar of the foundation, which, therefore, can be used with great advantage as a support.

In the drawings:

Fig. 1 is a section of the hot air chamber of the cooling installation in parallel to the machine axis in front of the cooler, the vertical part of the hot-air channel in front of the cooler, as well as the throttle valves for the cooling water and the collecting pipes being omitted.

Fig. 2 is a horizontal section, and

Fig. 3 is a section at right angles to the machine axis.

Referring to the drawings, the cooling air escapes from the air outlet terminal *a* of the turbo-generator *b* and flows through the hot air channel *c* to the cooler *d*, the elements of which it traverses in horizontal direction and thereafter enters the space *f* between the elements of the cooler *d* and the adjoining foundation pillars. The cold air conduit extending above the condenser *g* extends from this space *f*, returning the cooled air into the air inlet terminals *h* of

the turbo-generator *b* to start circulation afresh.

The horizontally arranged cooler elements of the cooler *d* can be separately cut out by means of the throttle valves *e* without the operations of the whole arrangement having to be interrupted on this account. *m* are water chambers arranged at the ends of the cooler elements.

As will be seen from Figs. 2 and 3 the cooler elements can be removed and re-inserted in the direction of the arrow *i* like a drawer.

As has already been said, a device is suitably provided, which permits of the shutting off of the surface taken up by the single cooler elements in certain cases, so that these can be put out of operation temporarily during working of the plant or be completely changed. For the sake of clarity this device was not shown in the drawings.

Instead of air any other neutral gas can, of course, flow in the cooling installation.

Having fully described my invention, what I claim is:—

1. Closed air circulation cooling system for electrical machinery comprising in combination an electrical machine, a foundation supporting said machine, a cooler having the form of a thin vertical wall arranged in front of the outer wall of said foundation, the side of said cooler, where the air escapes, extending in vertical direction, and freely accessible water chambers associated with said cooler and a cold air conduit and a hot air conduit extending between said cooler and said electrical machine, said two conduits being

curved to leave a large freely accessible space below said electrical machine and below said cold air conduit.

2. Closed air circulation cooling system for electrical machinery comprising in combination an electrical machine, a foundation supporting said machine, a cooler having the form of a thin vertical wall arranged in front of the outer wall of said foundation, the side of said cooler, where the air escapes, extending in vertical direction and in parallel to the axis of said electrical machine, freely accessible water chambers associated with said cooler and a cold air conduit and a hot air conduit extending between said cooler and said electrical machine, said two conduits being curved to leave a large freely accessible space below said electrical machine and below said cold air conduit.
